UNITED STATES PATENT OFFICE.

HENRI STEVEN, OF MONTEFURADO, SPAIN.

VALVELESS APPARATUS COMPRISING PISTONS HAVING AN ALTERNATING RECTILINEAR MOTION FOR DRAWING AND DELIVERING FLUIDS.

1,262,130.

Specification of Letters Patent. Patented Apr. 9, 1918.

Application filed April 25, 1916. Serial No. 93,484.

To all whom it may concern:

Be it known that I, HENRI STEVEN, a subject of the King of Spain, residing in Montefurado, in the Province of Lugo, in Spain, 5 have invented certain new and useful Improvements in Valveless Apparatus Comprising Pistons Having an Alternating Rectilinear Motion for Drawing and Delivering Fluids, of which the following is a specification.

This invention relates to valveless pumps, compressors or the like for fluids and gases of the type comprising a pair of communicating twin cylinders in which work a plurality of connected pistons which form separated piston chambers both coöperating with ports in the cylinders in such a way that suction and delivery, effected by the end pistons in each cylinder are controlled in either 10 cylinder by the intermediate distributing pistons of the respectively opposite cylinder.

As hitherto proposed the inlet and outlet respectively are arranged on the side of one cylinder and the fluid passing in and out 15 from the far cylinder has to pass through spaces formed by the intermediate pistons on the near cylinder. Each piston has a central orifice and the two multiple pistons in their travel double by half a stroke.

The object of the present invention which is applicable to pumps, compressors, meters or the like is to overcome the above disadvantage and it consists in placing the inlet and outlet in between the two cylinders and 20 in so arranging the connection to the two cylinders that a central orifice in each cylinder is not only in permanent communication with the central piston chamber but is also in permanent communication with piston 25 chambers above and below the central piston chamber in the respectively opposite cylinder so that the intermediate pistons may effectively distribute the fluid.

An embodiment of this invention is illustrated by way of example in the accompanying diagrammatic drawing. For the understanding of the operation the improved apparatus will be described on the assumption that it is worked as a pump.

As shown in the example, 1, 2 and 3 are the admission and delivery ports for the upper part of the cylinders A A'. 4, 5 and 6 are the admission and delivery ports for the lower part of the cylinders A A'.

7 is the suction duct and 8 is the delivery duct.

9 is the central orifice of the cylinder A communicating through the duct 7 with the orifices 10 and 11 of the cylinder A'.

12, 13 and 14 are a second set of admission and delivery orifices for the upper part of the cylinders A A'. 15, 16 and 17 for the lower part of the cylinders A A', and

18 is the central orifice of the cylinder A' communicating through the duct 8 with the orifices 19 and 20 of the cylinder A.

As indicated by the arrows, the admission is through port 29 in the duct 7 and not through the port 30, because it is assumed that the shaft S is rotating in the direction 70 of the arrow. However, if the crank shaft were rotating in the opposite direction, the admission would take place in the reverse way, namely through the duct 8, and the fluid would enter through the port 30, while 75 the delivery would take place through the duct 7 and the fluid pass out through the port 29.

In each cylinder there works a piston composed of superposed disks spaced apart from 80 one another; all these disks are fixed to one another.

Only one piston, namely the piston of the cylinder A', will be described, since the two pistons are similar to each other as regards 85 form and operation.

The piston is composed of four disks 21, 22, 23 and 24, fixed together by the rod N'.

The disks 21 and 24 are those which actually act as the piston, while the disks 22 90 and 23 act as shut-off and distributing devices.

The disk 22, in the position shown in the drawing, is located below the orifice 14, and consequently the latter is uncovered and 95 communicates with the orifice 10 through the piston chamber constituted by the space comprised between the disks 21 and 22. The fluid can therefore enter through the duct 7 and, passing through the duct 13 and the orifice 12, it enters the upper part of the cylinder A wherein suction is produced by the descent of the piston B. When the piston B', continuing to ascend, as indicated by its arrow, arrives at the middle of its stroke, 100 the disk 22 will cover the orifice 14, and, as the piston continues its ascent, the lower part of the disk 22 will uncover the orifice

14, whereby the latter orifice will be placed in communication with the central chamber of the piston B' (this chamber being comprised between its disks 22 and 23). When 5 the piston B' is in this position, the crank S'' has moved beyond its bottom dead center. The corresponding piston B moves in the opposite direction to that of the arrow of this piston. The fluid which up to this 10 moment has been sucked in by the disk 25, is now forced out by the latter through the orifices and ducts 12, 13 and 14. The fluid then passes between the disks 22 and 23 (that is to say, through the central chamber 15 of the piston), and enters through the orifice 18 into the duct 8, whence it passes out through the port 30.

The pistons have therefore to perform 20 two simultaneous functions: (1^a) the functions performed by their ends which act as pistons, and (2^a) the functions performed by the intermediate disks which act as distributors, the whole structure forming one entity fixed on the piston rod. The spaces 25 comprised between the disks, three in number, serve to establish communication between the orifices. These spaces may have suitable forms according as it is a question of acting upon liquids or gases, and the 30 whole structure may be made in one or more pieces of any shape, but such that there will be three cavities for establishing communications, and two projecting parts acting as the distributing device.

35 The mechanisms that serve to move the pistons may be constructed to suit the circumstances of each particular case. The pistons may also be driven by means of other pistons moving in similar cylinders, 40 by coupling them by means of rods. In these said other cylinders steam, for instance, may be employed as the direct driving means.

The four disks that constitute the entity

of each of these pistons may be provided 45 with packing like that used in steam engine pistons for insuring tightness. By this means the efficiency of the apparatus is increased because each of these pistons constitutes as it were four superposed simple 50 pistons spaced apart.

What I claim is:—

1. A valveless pump compressor or the like comprising in combination a pair of communicating twin cylinders, a plurality of connected pistons in each cylinder forming three separate piston chambers, means whereby suction and delivery effected by the end pistons are controlled in either cylinder by the intermediate distributing piston of 60 the respective opposite cylinder, a main outlet and a main inlet placed in between the two cylinders, a central orifice in each cylinder, and connections to the two cylinders such that the said central orifice is not only 65 in permanent communication with the central piston chamber, but is also in permanent communication with the piston chambers above and below the central piston chamber in the respective opposite cylinder. 70

2. A valveless pump, compressor or the like comprising in combination a pair of communicating twin cylinders, a compound piston in each forming three separate chambers, an orifice midway in the length of each cylinder, and in permanent communication with the central piston chamber, two orifices communicating permanently with each of the end chambers of the piston, two distributing ports located one on each side of the said central orifice, these orifices communicating with the ends of the respective opposite cylinder and a main outlet and a main inlet placed in between the two cylinders. 75

80 In testimony whereof I have signed my name to this specification.

H. STEVEN.
